UNITED STATES PATENT OFFICE.

JOSEF CATHREIN, OF MUNICH, GERMANY, ASSIGNOR TO IGNAZ FRIEDINGER,
OF OBERTHAL, NEAR LINZ, AUSTRIA-HUNGARY.

SKIRT-PROTECTOR.

SPECIFICATION forming part of Letters Patent No. 707,387, dated August 19, 1902.

Application filed April 28, 1902. Serial No. 105,112. (No model.)

To all whom it may concern:

Be it known that I, JOSEF CATHREIN, a citizen of Austria-Hungary, residing at Munich, Bavaria, Germany, have invented certain new and useful Improvements in Skirt-Protectors; and I do hereby declare the following to be a full, clear, and exact description of the invention, such as will enable others skilled in the art to which it appertains to make and use the same.

The present invention relates to ladies' gowns; and it consists more particularly in improved means for protecting the lower edge of the same against wear and tear in consequence of contact with the pavement or road or with the floor.

The invention comprises the details of construction hereinafter set forth, and particularly pointed out in the claims.

20 In order to render the present specification easily intelligible, reference is had to the accompanying drawings, in which similar letters of reference denote similar parts throughout the several views.

25 Figure 1 is a side elevation of the lower part of a dress, showing the means hitherto employed for protecting the same. Fig. 2 is a section drawn to a larger scale, showing the said means more in detail. Fig. 3 is a side elevation showing the improved means according to the present invention; Fig. 4, a detail section, drawn to an enlarged scale, taken through the lower part of the train; and Fig. 30 5 is an elevation of the inner side of the train, showing a modified form of the device.

In ladies' gowns which are not foot-free, and especially those having trains, the disadvantage is noticeable that the contact with the floor or pavement of the under side of the 40 gown causes the threads to wear through and ruins the dress at the points indicated by *a* in Fig. 2. The dust and mud cling directly to the stuff, rendering the same hard and liable to break and also rendering the cleaning very difficult. Hitherto a braid or ruche of brush-like trimming, as at *b*, Figs. 1 and 2, has been attached around the edge of the dress and train; but this does not effectually fulfil the purpose in view, because it does not 45 protect the point of contact of the gown with the floor, as will be seen on reference to Fig. 2.

According to the present invention three or four or any suitable number of rows of a brush-like braid or ruche are attached around

the interior lower parts of the gown, as at *c* 55 in Figs. 3 and 4. Thus the lower part of the train *d* will be held off the floor or pavement by the brush trimming *c* and any dust or mud will be held off by the brushes *c*.

There is another advantage accruing from 60 the present invention, and it is that the brushes inside the train will pass gently over the pavement and will not raise the dust in the same manner as would the gown on contact with the street. The brush trimming 65 will only wear at the points indicated in dotted lines in Fig. 4 and may be very easily cleaned when muddy, wet, or dusty. The material of which the dress is made will be entirely prevented from contact with the 70 street or floor, being carried by the brush-like trimming.

It will be noticed that my device presents a series of overlapping rows, so that the fabric will at no point touch the ground or floor 75 and the train will fall in a graceful sweep instead of undulating or with a rising edge.

As illustrated in Fig. 5, in order to render the braid or ruche of less weight the brushes may be made after the manner of tassels, as 80 at *b'*.

I claim as my invention—

1. A skirt-protector consisting of a series of rows of overlapping brush-like braid secured to the under side of the skirt and having 85 the bristles projecting rearwardly and downwardly.

2. A skirt-protector consisting of a series of rows of brushes secured to the under side of the skirt, the bristles of each row overlapping 90 the adjacent row and projecting in the general direction of the edge of the skirt at less than a right angle to the skirt-body at the point of attachment.

3. A skirt-protector consisting of a series 95 of overlapping rows of brush-like fabric secured to the under side of the skirt and extending for an appreciable distance upward from the bottom edge thereof, so arranged that the bristles will lie approximately parallel with the skirt and project toward the edge of the skirt.

In testimony whereof I affix my signature in presence of two witnesses.

JOSEF CATHREIN.
